(No Model.)

F. T. ROBINSON.
BOTTLE STOPPER.

No. 599,112.

Patented Feb. 15, 1898.

UNITED STATES PATENT OFFICE.

FRANK T. ROBINSON, OF CHICAGO, ILLINOIS.

BOTTLE-STOPPER.

SPECIFICATION forming part of Letters Patent No. 599,112, dated February 15, 1898.

Application filed November 11, 1895. Serial No. 568,517. (No model.)

To all whom it may concern:

Be it known that I, FRANK T. ROBINSON, a citizen of the United States, residing at Chicago, in the county of Cook and State of Illinois, have invented certain new and useful 5 Improvements in Bottle-Stoppers, of which the following is a specification.

The present invention relates to that class of bottle-stoppers that are intended to prevent the fraudulent refilling of bottles and other packages that have once been legitimately filled with liquors of established reputation. In many stoppers of this class there is a valve, a ring secured in the neck of the 15 bottle and having upon its top a seat for the valve, and a part, hereinafter called a "baffle," located above the valve-seat ring for preventing access to the valve.

One object of the invention is to provide a 20 simple and effective means for securing together the valve-seat ring and baffle, and this object I accomplish by providing each of them with portions that fit against the inner surface of the neck of the bottle, and I provide 25 each of these portions with two or more perforations, the perforations of one being arranged opposite the perforations of the other, so as to be in positions to receive the legs of 30 metallic staples, the backs of which are received within grooves formed in the outer surfaces of said perforated portions.

Another object of the invention is to provide improved means for securing the stopper in place in the neck of the bottle, and this 35 object I accomplish by providing the stopper and the neck of the bottle with circumferential grooves, which when the stopper is in place are opposite each other, and in these 40 grooves I place an elastic ring which breaks the joint between the stopper and the neck of the bottle, and I arrange in the groove of the stopper, within the elastic ring, a metallic 45 spring-ring so constructed that it has a constant tendency to expand.

Another object of the invention is to provide a stopper of this class with means for preventing the valve from being thrown from its seat by "chucking" the bottle, or, in other words, giving it a quick jiggling or jerking 50 movement in the direction of its length, and in accomplishing this object I arrange above the valve what is hereinafter termed a "pend-

ent strut," being a strut whose upper end is loosely supported and whose lower end is free to swing in all directions and is in close proximity to the top of the valve when the bottle is in upright position.

Belonging to the genus above named there is a species of stopper in which there is a ring having upon its top side a valve-seat, a valve located above the valve-seat ring, a weight located below the valve-seat ring, and a flexible connection between the valve and weight. The invention relates in part to stoppers of this species; and the object of this part of the 65 invention is, generally stated, to improve their construction.

To these ends the invention consists in the features of novelty that are particularly pointed out in the claims hereinafter, and in order that it may be fully understood I will describe it with reference to the accompanying drawings, which are made a part of this specification, and in which—

Figure 1 is a vertical section of the upper 75 portion of a bottle and of a stopper embodying the invention in place therein, the parts being shown in the positions that they occupy when the bottle is in upright position. Fig. 2 is a similar section of the same parts, showing them by full lines in the positions that they occupy when the bottle is tipped almost to pouring position and by dotted lines in the 80 positions that they occupy after the pouring position is reached. Figs. 3 and 4 are horizontal sections thereof on the lines 3 3 and 4 4, respectively, Fig. 1. Fig. 5 is a view of the 85 spring-ring used for assisting in holding the stopper in place in the neck of the bottle.

A represents the neck of the bottle; B, a 90 ring hereinafter called the "valve-seat" ring; C, a valve located above the valve-seat ring, and D a part, hereinafter called the "baffle," located above the valve. The neck of the bottle is provided on its interior with a circumferential groove which when the stopper is in place is opposite a corresponding groove in the valve-seat ring. Arranged in the groove of the valve-seat ring is an open spring-ring E, so constructed that it has a constant 95 tendency to expand circumferentially, said ring being preferably of about semicircular shape in cross-section and provided in its edges with kerfs or cuts e, without which it 100

would not be of sufficient flexibility, owing to its cross-sectional shape. Within the hollow of this ring and surrounding it is an elastic ring F, which projects into the groove in the neck of the bottle and serves the double purpose of a gasket for preventing leakage past the stopper and means for preventing the stopper from being withdrawn. It is of course possible to destroy the ring by means of acids, and it is in order to guard against this that the metallic spring-ring E is provided. So long as the elastic ring F remains intact it will confine the metallic ring to the groove of the stopper; but as soon as the elastic ring disintegrates the expansive force of the metallic ring will cause it to project partly beyond the groove in the stopper and enter the groove in the neck of the bottle, and thus prevent the stopper from being withdrawn.

As shown in the drawings, the valve-seat ring is provided on its top side with an annular flange b, and the baffle is provided on its under side with an annular flange d, which flanges are equal in external dimensions to the internal dimensions of the neck of the bottle, so that they fit snugly. The flanges come together and result in a chamber X, in which the valve C is located. In order to secure the baffle to the valve-seat ring, these flanges are provided with perforations properly arranged for receiving the legs of staples G, the backs of which staples fit in grooves or depressions formed for them in the flanges. These grooves or depressions are just sufficient in depth to receive the backs of the staples, so that when the parts are in place, as shown in the drawings, the staples cannot possibly move in any direction, and consequently the baffle cannot be pulled away from the valve-seat ring. In the drawings I have shown two of these staples; but a greater number may be used, if desired.

H is a pendent strut the upper end of which is loosely connected to the baffle and the lower end of which is free to swing in any direction and is in close proximity to the top of the valve when the bottle is in upright position. The means shown in the drawings for securing this strut to the baffle is a staple h, passing through a perforation in the upper end of the strut and having its legs secured to a plate h', which is sprung into place within the baffle. It will be seen that until the bottle is tipped to such position that the lower end of the strut is no longer opposite the top of the valve it will be impossible for the valve to move away from its seat, and hence it follows that while the bottle is in upright position it will not be possible to throw the valve from its seat by chucking it in the manner already described.

Located below the valve-seat ring is a weight I, which is connected to the valve by means of a flexible ligament J, preferably a silken strand. This weight I prefer to construct of a glass disk i, having a central perforation, through which passes and in which is secured a hollow stem i', preferably of alu-

minium, and a float i", preferably a piece of cork, arranged upon the under side of the disk i and having in its top side a hole or 70 socket, in which the lower end of the stem i' fits, the float being perforated and the ligament J being passed through the hollow stem i' and the perforation of the float and knotted on the under side, as shown at j. The ligament J is of such length that when the bottle is tipped to a sufficient extent the stem i' will come in contact with an annular flange or 75 projection B', which extends downward from the under side of the valve-seat ring, and without the floating feature of the weight the valve would not unseat until the bottle is tipped to such position that the center of gravity of the weight passed its point of bearing upon the projection B'. This would be objectionable, because it would postpone the unseating of the valve until the bottle had almost reached a vertical position. To hasten the unseating of the valve is the object of the floating feature of the weight, and by reason 80 of it when the float is submerged a certain distance its buoyancy will cause it to move the weight up against the bottom of the flange B', as indicated by dotted lines, and thereby permit the valve to fall away from its seat. 85 The float is not, however, of sufficient buoyancy to float the weight, considered as a whole, but only of sufficient buoyancy to aid its movement from the position shown by full lines in Fig. 2 to the position indicated by 90 dotted lines.

Having thus described my invention, the following is what I claim as new therein and desire to secure by Letters Patent:

1. The combination with a bottle having 105 within its neck a circumferential groove and a stopper having a corresponding groove, of an open metallic spring-ring occupying the groove of the stopper, and an elastic ring surrounding the spring-ring and projecting into 110 the groove in the neck of the bottle, substantially as set forth.

2. The combination with a bottle having within its neck a circumferential groove and a stopper having a corresponding groove, of an 115 open metallic spring-ring of approximately semicircular shape in cross-section occupying the groove of the stopper, and an elastic ring surrounding and fitting in the spring-ring and projecting into the groove in the neck of the 120 bottle, substantially as set forth.

3. The combination with a bottle, of a stopper having, in combination, a valve, a valve-seat ring having an annular flange extending upward therefrom and fitting the neck of the 125 bottle, a baffle having an annular flange extending downward therefrom and fitting the neck of the bottle, oppositely-located perforations formed in said flanges, and staples each having one of its legs fitting in a perforation of one of the flanges and its other leg fitting in a perforation of the other flange, 130 said flanges being grooved to receive the back of the staple, substantially as set forth.

4. In a bottle-stopper, the combination with a valve, of a strut arranged above it, means by which the upper end of the strut is loosely supported so as to permit its lower end to swing freely in all directions, and means for positively preventing any upward endwise movement of the strut, the lower end of the strut being in close proximity to the top of the valve, substantially as set forth. 30
5. In a stopper the combination with a valve and a valve-seat, of a fixed baffle arranged above the valve for preventing access thereto, and a strut having its upper end loosely connected to said baffle so that its lower end is free to swing in all directions, the lower end of the strut being in proximity to the top of the valve, and the strut being prevented by the fixed baffle from moving upward, substantially as set forth. 35
- 10 6. In a stopper, the combination of a valve-seat, a valve located above it, a weight located below it, means connecting the valve and weight, and a float secured to the weight, the weight and float combined being slightly heavier than the liquid which they displace, substantially as set forth. 40
- 15 7. In a bottle-stopper the combination of a valve-seat, a valve arranged above it, a weight arranged below it, a flexible ligament connecting the valve and weight, and a float connected to the weight, the weight and float combined being slightly heavier than the liquid which they displace, substantially as set forth. 45
- 20 8. In a bottle-stopper, the combination of a valve-seat, a valve located above it, a weight located below it, means connecting the valve and weight, and a float secured to the under side of the weight, the weight and float combined being slightly heavier than the liquid which they displace, substantially as set forth. 50
- 25 9. In a bottle-stopper, the combination of a valve-seat, a valve arranged above it, a weight arranged below it, and having a rigid stem projecting upward, a flexible ligament connecting the upper end of said stem and the valve, an annular bearing for the stem, and a float secured to the weight, the weight and float combined being slightly heavier than the liquid which they displace, substantially as set forth. 55
7. In a bottle-stopper the combination of a valve-seat, a valve arranged above it, a weight
